UNITED STATES PATENT OFFICE

2,363,072

THERMOCOUPLE AND PILOT BURNER

Harold A. Mantz, Milwaukee, Wis., assignor to
Milwaukee Gas Specialty Company, Milwaukee,
Wis., a corporation of Wisconsin

Original application April 13, 1939, Serial No.
267,733, now Patent No. 2,267,742, dated De-
cember 30, 1941. Divided and this application
November 14, 1941, Serial No. 419,043

2 Claims. (Cl. 136—4)

This invention relates to a thermocouple and pilot burner.

The present application is a division of my copending application, Serial No. 267,733, filed April 13, 1939, now Patent No. 2,267,742, issued December 30, 1941.

One of the main objects of the invention is to provide a combined thermocouple and pilot burner which is effective and reliable in operation and, at the same time, is simple and compact in construction and relatively inexpensive to build, assemble, and install.

It is also an object of the invention to provide a thermocouple and pilot burner as a unitary assembly that may be mounted as a unit, and in which the desired position of the thermocouple relative to the pilot flame is at all times assured; also a device of the character set forth having an improved relation and improved forms of connection between the various parts.

Further objects and advantages of the invention will appear from the following detailed description, taken in connection with the accompanying drawing in which:

Figure 1 is a longitudinal sectional view through a combined thermocouple and pilot burner device embodying the present invention;

Figure 2 is a view similar to Figure 1, showing a modification of the device; and

Figure 3 is a view similar to Figure 1, showing a second modification of the device.

In the embodiment of the invention illustrated in Figure 1, the outer end of the metallic tubular fuel supply lead 46 is secured in a metallic bracket member 48, from which it is electrically insulated at 300. The fuel supplied by the tube 46, which is preferably flexible to permit bending or turning the same or leading it around corners for disposition of the thermocouple and pilot burner as desired, passes outwardly through a port 48, and when ignited, forms a pilot flame. The bracket 48 has an integral inverted and generally channel or U-shaped shield 51 which confines the pilot flame so that the hot junction of the thermocouple will be subject to the heat of the pilot flame as long as the pilot burner is lighted.

The thermocouple comprises an external metallic tubular thermocouple element 52 clamped at 53 in the bracket 48 and an internal thermocouple element 54 formed of dissimilar material and joined to the outer end of the external thermocouple element to form a thermal junction 56 adapted to be heated by the pilot flame. The projecting inner end of the internal ther-

mocouple element 54 is connected by a short lead 59 to tube 46, which extends through a tubular metal casing 60, from which it is electrically insulated at 300a, to the desired position and is connected directly to one lead of a coil of an electromagnet (not shown). The tubular casing 60 is connected in circuit with the external thermocouple element 52 through the bracket 48, as will appear presently, and constitutes the lead conductor between the other lead of the coil of the electromagnet and the external thermocouple element 52.

The bracket 48 is clamped at 64 to the outer end of the tubular casing 60, in close electrical conducting contact therewith, and is supported upon an angular supporting bracket 65 by a screw 66 which cooperates with a slot 67 in the extending leg of the bracket to permit adjustment of the position of the thermocouple and pilot burner. The depending leg of the bracket 65 is secured at 69 to the wall 70, which may be the wall of a space heater, hot water heater, or any other suitable heater, or the part indicated at 70 may be any other suitable support.

25 In the embodiment of the invention illustrated in Figure 2, the metallic tubular fuel supply tube 75, which is preferably flexible for the purposes hereinbefore set forth, is secured in a jet member 76, which jet member in turn is secured in the metallic bracket 77, from which it is electrically insulated at 302. A venturi 78 is mounted in the bracket 77 in axial alignment with the orifice 79 at the outer end of the jet member 76 and spaced outwardly therefrom. Where the fuel is of a character, such as gas, requiring admixture of air therewith, the air necessary to provide the desired gaseous mixture is admitted through an air inlet at 80. The air admitted through the inlet 80 and the fuel that issues from the orifice 79 pass outwardly through the venturi 78 into the mixing chamber 82. The resulting gaseous mixture passes outwardly through a port 84 at the outer end of the tubular portion of the bracket 77 and, when ignited, forms the pilot flame.

The thermocouple comprises an external metallic tubular thermocouple element 88 secured at 89 in the bracket 77 and an internal thermocouple element 90 formed of dissimilar material and joined to the outer end of the external thermocouple element to form a thermal junction 92 adapted to be heated by the pilot flame.

In Figure 2 the short lead conductor 95 connects the internal thermocouple element 90 to

the metallic fuel supply tube 75, this tube 75, in addition to supplying fuel for the burner, then extending to the desired position and being connected to one lead of the coil of the electromagnet as in the form of Figure 1. As before, the tube 75 is electrically insulated at 302a from casing 96, and the latter is connected in circuit with the external thermocouple element 88 through the bracket 77, as will appear presently, so that the casing 96 will constitute the lead conductor between the other lead of the coil of the electromagnet and the external thermocouple element 88.

The bracket 77 is clamped at 98 to the outer end of the tubular casing 96 in electrical conducting contact therewith, and is supported upon an angular bracket 100, being shown as mounted thereon by means of a screw 102 which cooperates with a slot 103 in the extending leg of the bracket to permit adjustment of the position of the thermocouple and pilot burner. The depending leg of the bracket 100 is secured at 104 to the wall 105, which may be the wall of a space heater, hot water heater, or any other suitable heater, or the part indicated at 105 may be any other suitable support.

The outer end of the tubular portion of the bracket 77 has a narrow slot 110 opening inwardly from the port 84, through which the pilot flame is directed upon the junction 92 of the thermocouple. The bracket 77 has integral depending flanges 112 extending down along opposite sides of the thermocouple so that the pilot flame which is directed through the slot 110 is confined and proper heating of the thermocouple at all times thereby assured.

In the embodiment of the invention illustrated in Figure 3, the metallic tubular fuel supply lead 115 is secured in a metallic bracket member 118, from which it is electrically insulated at 304. The fuel supplied by the tube 115, which is preferably flexible to permit bending or turning the same or leading it around corners for disposition of the thermocouple and pilot burner as desired, passes outwardly into a passage 119 formed in the depending portion of the bracket 118 and is directed obliquely through an oblique port 120 toward the outer end of the thermocouple. The bracket 118 has an integral inverted or generally channel or U-shaped shield 121 into which the pilot flame is directed, so that the hot junction of the thermocouple will be subject to the heat of the pilot flame as long as the pilot burner is lighted.

The thermocouple comprises an external metallic tubular thermocouple element 125 secured at 126 in the bracket 118 and an internal thermocouple element 128 joined to the outer end of the external thermocouple element to form a thermal junction 130 adapted to be heated by the pilot flame. The thermocouple is disposed longitudinally within the shield 121, as shown.

In Figure 3 the short lead conductor 136 connects the internal thermocouple element 128 to the metallic fuel supply tube 115, this tube, being insulated, as before, at 304a, from the tubular metal casing 138. The tubular casing 138 is connected in circuit with the external thermocouple element 125 through the bracket 118, as will appear presently, so that the casing 138 will constitute the lead conductor between the other lead of the coil of the electromagnet and the external thermocouple element 125.

The bracket 118 is clamped at 142 to the outer end of the tubular casing 138, in electrical conducting contact therewith. The flexible tubular casing 138 serves to support the thermocouple and pilot burner in the desired position notwithstanding its flexibility and the flexibility of the tubular lead 115, but it is to be understood that supporting bracket means may be provided as suitable or desired.

I do not intend to be limited to the precise details shown or described.

I claim:

1. In means of the character described, a flexible metallic tubular sheath, a metallic bracket secured upon one end of said sheath in electrical conducting relation thereto, a pilot burner and a thermoelectric generator supported by said bracket in cooperating relation with one element of the thermoelectric generator in electrical conducting relation to said bracket, and a flexible metallic fuel supply tube within and electrically insulated from said sheath anchored in and electrically insulated from said bracket in position for supplying fuel to the pilot burner, said bracket, restraining said sheath and said tube against relative movement, said sheath being available as a lead for one element of the thermoelectric generator and said tube being available as a lead for the other element of the thermoelectric generator.

2. In means of the character described, a flexible metallic tubular sheath, a metallic bracket secured upon one end of said sheath, a pilot burner and a thermoelectric generator supported by said bracket in cooperating relation, and a flexible metallic fuel supply tube within and electrically insulated from said sheath anchored in said bracket in position for supplying fuel to the pilot burner, said bracket restraining said sheath and said tube against relative movement, one of said sheath and said tube being electrically connected to said bracket and available as a lead for one element of the thermoelectric generator and the other of said sheath and said tube being electrically insulated from said bracket and available as a lead for the other element of the thermoelectric generator.
